UNITED STATES PATENT OFFICE.

LAWRENCE ADKINSON SMITH, OF PORT GIBSON, MISSISSIPPI.

HUMIDIFIER.

1,368,365.

Specification of Letters Patent. Patented Feb. 15, 1921.

Application filed February 8, 1919. Serial No. 275,820.

To all whom it may concern:

Be it known that I, LAWRENCE A. SMITH, a citizen of the United States, and a resident of Port Gibson, in the county of Clai- 5 borne and State of Mississippi, have invented certain new and useful Improvements in Humidifiers, of which the following is a specification.

My invention is an improvement in hu- 10 midifiers, and has for its object to provide a device of the character specified, small and portable, and capable of being carried in the pocket if desired, by means of which a cigar may be simultaneously moistened 15 and impregnated with a flavoring, as, for instance, that of a high grade of tobacco extract, by driving a blast of air laden with the flavoring through the cigar from the tuck end to the other end.

20 A further object of the invention is to provide means for humidifying and flavoring cigars and tobacco in quantities by a similar process.

In the drawings:

25 Figure 1 is a longitudinal section of the improved humidifier;

Fig. 2 is an end view looking at the left;

Fig. 3 is an enlarged sectional detail showing the check valve;

30 Fig. 4 is a similar detail showing the air outlets;

Fig. 5 is a front view of the check valve seat;

Fig. 6 is a diagrammatic view of an ap- 35 paratus for humidifying and flavoring ci- gars and tobacco in quantities.

In the present embodiment of the invention a suitable casing 1 is provided, prefer- 40 ably of cylindrical form, having one end concaved as indicated at 2 to form a tapering or conical seat for the tuck end of the cigar. At the other end there is a nipple 3, and within the casing is arranged a pair 45 of concentric tubes 4 and 5, the said tubes being concentric with the casing.

At the end adjacent to the seat 2 the tube 4 is rigidly connected with the seat, the said tube 5 being connected with and com- 50 municating with the seat at the apex. The tube 5 opens through the seat 2 at the center thereof, so that air passing through the tube 5 may enter the cut end of a cigar held on the seat. Near the nipple 3 the tube 5 passes out of the tube 4 and is bent around 55 the same, as indicated at 6, and at the said end the tube 5 has an opening 7 which forms

a communication between the interior of the casing 1 and the said tube 5.

The tube 4 has a series of openings 8 at the end adjacent to the seat, and the casing 60 is adapted to be filled with a flavoring ex- tract to about half its depth, as indicated by the shade lines in Fig. 1, by means of the openings 8, the extract being poured into the open end of the tube 4.

The said open end is normally closed 65 by a cap 9 threaded on to the tube 4, having a narrow inlet port 10. A bar 11 is ar- ranged transversely of the end of the tube 4, the said bar being provided with a con- 70 cavity 12 intermediate its ends for engage- ment by the check valve 13. This check valve 13 is a sphere, and the lateral enlarge- 75 ment 12 forms a seat for the valve. Nor- mally, there is space between the bar 11 and the cap sufficient to permit the valve 13 to remain unseated from over the port 10, but the valve will prevent the escape of the liquid extract from the casing 1, while per- 80mitting the free entrance of air.

In practice, the cap may be removed to 85 permit the insertion of the flavoring extract and with the extract in place the humidifier is ready for use. In using the device, the cigar is clipped and the tuck end is inserted 90 in the seat 2. A blast of air is now driven into the tube 4 through the inlet 10. This air passes down between the tubes 4 and 5, escaping at the openings 8, passes up through the extract into the open space of 95 the interior of the casing 1, into the opening 7 of the tube 5, and through the said tube into the cigar, properly moistening the same and thoroughly flavoring the con- 100 tents thereof. The air may be supplied by blowing into the opening 10, or by means of a pump of suitable construction, as for instance, a bulb. If desired, the tube could be connected with any suitable source of air under pressure.

In Fig. 6 is shown an apparatus for hu- 105 midifying and flavoring cigars and tobacco in quantities. This apparatus comprises a casing or exhaust chamber 15, a container 16 for the tobacco or cigars to be flavored and humified and a container 17 for the liquid. A pipe 18 connects the chambers 15 and 16 and a pipe 19 connects the chambers 16 and 17, each pipe being controlled by a valve indicated at 20 and 21, respectively. The 110 container 17 has an inlet pipe 22, opening in the top thereof and extending to near

the bottom, as shown, and a pump 23 or other means for exhausting the air in the chamber 15 is arranged in the said chamber, the pump being operated by the usual handle 24.

In operation, the cigars or tobacco to be humidified and flavored are placed in the container 16. The container 17 is partially filled with liquid, as shown, and the air is 10 partially exhausted from the chamber 15. When now the valves 20 and 21 are opened a current of air laden with the flavoring matter is drawn through the casing 16, contacting with the tobacco or cigars therein, 15 and thoroughly humidifying and flavoring the same. The process may be reversed by putting air under pressure in the chamber 15, and passing it in the opposite direction, it being understood that in this case the

liquid container would be arranged between the tobacco container and the exhaust chamber.

I claim:

1. A device of the character specified comprising a casing adapted to contain a 25 flavoring extract, means for receiving the tobacco to be flavored and humidified, and means for driving a blast of air through the flavoring extract and into and through the tobacco.

2. A method of humidifying and flavoring cigars or tobacco, which consists in passing a current of air through a solution of flavoring extract to thoroughly impregnate the air with the extract and in forcing 35 said air through the tobacco or cigars to be flavored.

LAWRENCE ADKINSON SMITH.
